United States Patent [19]
Iino

US00D336286S

[11] Patent Number: Des. 336,286
[45] Date of Patent: ** Jun. 8, 1993

[54] ELECTRONIC COMPUTER

[75] Inventor: Masaaki Iino, Yokohama, Japan

[73] Assignee: Kabushiki Kaisha Toshiba,
Kanagawa, Japan

[**] Term: 14 Years

[21] Appl. No.: 611,958

[22] Filed: Nov. 13, 1990

[30] Foreign Application Priority Data

May 14, 1990 [JP] Japan 2-15730
